UNITED STATES PATENT OFFICE

2,436,131

REFRACTORY TILE

Nels E. Werner, Detroit, Mich., assignor to Bigelow-Liptak Corporation, Detroit, Mich., a corporation of Michigan

Application September 30, 1943, Serial No. 504,349

1 Claim. (Cl. 72—25)

The current invention pertains to a novel and improved form or style of refractory blocks or tiles designed more or less for general use but particularly adapted for employment in a protective wall mounted on the inner surface of the metal or steel shell of a tank, vessel, or comparable receptacle to shield and protect such container from the effects of overheating and from the consequences of the presence of a condensate which would otherwise be likely to cause deterioration and ultimate failure of the metal wall of the vessel or chamber if allowed to form thereon.

The invention pertains more especially to refractory-tiles used for the proper preservation of carbon-steel shells or walls of storage-hoppers, catalyst-regenerator chambers, reactor-chambers, hot-gas and catalyst piping and hot-air piping employed in the catalytic-processes in the hydrocarbon chemical industry.

In order to enable those skilled in the art of refractory-tiles and protective walls to understand this invention and the advantages accruing from its employment, a present preferred embodiment of the invention has been illustrated in detail in the accompanying drawing to which reference should be had in connection with the following description and in which drawing the same parts or elements in the several views have been designated by like reference characters.

In this drawing:

Figure 1 is a perspective view of the new tile; Figure 2 is a longitudinal, central section through the tile;

Figure 3 is a fragmentary perspective view looking somewhat upwardly at the lower end of the tile;

Figure 4 is a top plan view of the tile; and

Figure 5 shows the manner of mounting this form of tile, this figure illustrating the top portion of one such tile and the bottom portion of the next higher tile.

As is clearly portrayed in the drawing, the novel and unique tile, composed of a single integral member, includes a back or outer, generally-rectangular section or portion 11 and a similar, parallel, front or inner section or portion 12 offset or displaced somewhat laterally or transversely of the companion part 11, thereby providing along one longitudinal edge of the tile, a lengthwise rib 13 forming part of the rear section 11 and supplying along the opposite edge of the tile a complementary, lengthwise space 14 of substantially the same dimensions as those of the rib and adapted, in the completed wall to receive the rib of the next adjacent tile, the illustrated rib 13

being designed to fit in the groove of its contiguous tile, whereby like tiles may be fitted together with offset joints between them.

As is shown, the back-section 11 is somewhat thicker than the displaced front-section 12, and the extreme, top, upstanding part 15 of the latter and the terminal, bottom depending portion 16 of the front-section are both of substantially-equal thickness slightly less than that of the main intermediate body of such forward section 12, the front face of which is flush throughout.

The rear surface of the back-section and the front face of the forward-section are substantially parallel as illustrated.

As is clearly presented, the top of section 11 and a minor part of the top of section 12 are shaped to unitedly form a double-depth groove parallel with the rear and front surfaces of the tile, open at both opposite ends, and having a partially-curved surface 17, a flat bottom 18, an upright surface 19, a plane elevated surface 21, and a final erect surface 22, the top faces of parts 11 and 15 being on substantially the same plane at a right-angle to the lengthwise dimension of the tile.

In use, the deep portion of such groove receives a depending flange of a horizontal retaining metal-bar 37 and the flat surface 21 and the top part of 15 support an intermediate refractory-tile 43 of the shape and style shown in Figure 5, which illustration also depicts a section of a metal column 31 and a section of insulation 41.

The bottom of section 11 and a relatively-minor portion of the part 16 are cut away or omitted to provide a groove 23 parallel to the front and back surfaces of the tile, substantially-rectangular in cross-section, and open at both ends, it being noted that the part 16 extends down a short distance further than the bottom surface 24 of section 11, the latter at this position constituting a depending rib 25 rectangular in cross-section.

In the finished protective-wall, such bottom groove 23 accommodates an upstanding flange of another supporting metallic-bar of the framework and a part of another of the intermediate tiles referred to.

The novel tile under detailed consideration is so constructed that each of its parts performs a valuable function either in positioning the tile in place in the wall or in the completed wall itself.

This application constitutes a continuation in part of my co-pending patent application Serial

No. 470,992, Lined containers, filed January 1, 1943.

Obviously, the invention, as set forth in the appended claim, is not necessarily limited and restricted to the precise structural details shown and described and these may be modified somewhat, without departure from the substance and essence of the invention and without the loss of its substantial benefits and advantages.

I claim:

A solid refractory-tile substantially longer than its width and thickness and having a rear rectangular parallelopiped section and a front rectangular parallelopiped section parallel and integral with said rear section, said front and rear sections being offset laterally with relation to one another providing an outstanding rib along one longitudinal edge of the tile and a correlative space along the opposite longitudinal edge of the tile adapted to receive the corresponding rib of a like tile, the edges of each offset having plane parallel surfaces, the upper end of the tile having a groove parallel to the front and back surfaces of the tile, said groove having two parallel communicating longitudinal parts of different depths, the greater depth part of said groove being located in and extending the full width of said rear section and being to the

rear of the lesser depth part of the groove, the rear wall of said greater depth part being curved longitudinally forwardly downwardly of the tile for the purpose of bracing strength, the bottom of said lesser depth part of said groove being located in both sections and being a plane surface at a right angle to the front surface of the tile, the front wall of said lesser depth part of said groove being a plane surface parallel to the front surface of the tile, the bottom end of said tile having a groove parallel to the front and back surfaces of the tile, and the bottom end of said front section of said tile extending lengthwise beyond the corresponding end of said rear section of the tile.

NELS E. WERNER.
